UNITED STATES PATENT OFFICE.

ELBERT W. JODREY, OF LYNN, MASSACHUSETTS, ASSIGNOR TO GENERAL ELECTRIC COMPANY, A CORPORATION OF NEW YORK.

COIL FOR ELECTRICAL PURPOSES.

957,213.

Specification of Letters Patent. Patented May 10, 1910.

Application filed October 26, 1905. Serial No. 264,556.

To all whom it may concern:

Be it known that I, ELBERT W. JODREY, a citizen of the United States, residing at Lynn, county of Essex, and State of Massachusetts, have invented certain new and useful Improvements in Coils for Electrical Purposes, of which the following is a specification.

My present invention relates to coils or 10 windings and more particularly to a coil or winding of insulated wire for electrical purposes, and comprises certain novel and useful features of construction and arrangement of the coil and its support and terminals.

The various features of novelty which characterize my invention are pointed out with particularity in the claims annexed to and forming a part of this specification. 20 For a better understanding of my invention, however, reference may be had to the accompanying drawings and descriptive matter in which I have illustrated and described one of the forms in which my invention may be 25 embodied.

Of the drawings, Figure 1 is a plan view of a finished coil; Fig. 2 is a sectional elevation of the coil shown in Fig. 1; Fig. 3 is a plan view of the coil shown in Figs. 1 and 30 2 when partly constructed; Fig. 4 is an end elevation of the coil with a portion in section; Fig. 5 is an elevation on an enlarged scale showing a partly finished terminal connection; and Fig. 6 is a similar view showing 35 a finished terminal connection.

In the particular embodiment of my invention disclosed in the drawings, 1 represents the coil support which may be formed of any suitable material, but which I have 40 advantageously formed of a sheet of paper, press-board, or the like rolled into a tube with the layers of the tube glued together. The coil shown comprises an inner section or layer of winding 2 and an outer section 45 3, sections 2 and 3 being separated by a layer of insulation 4. The insulation 4 I have advantageously made of a sheet or strip of paper, cloth, or the like wrapped about the section 2. The inner end 5 of the 50 insulated wire forming the coil section 2 is secured to a terminal connector 6 which is in turn secured to the support 1 and has secured to it a terminal conductor 7. The outer end 8 of the wire forming the coil

section 2 is secured to a strip of conducting material 9 located between layers of insulation 4. The inner end 10 of the insulated conductor forming the coil section 3 is secured to a terminal connector 6' connected to the support 1 and having a terminal conductor 7' secured to it in the same manner as the connector 6. The outer end 11 of the conductor forming the outer coil section 3 is secured to the member 9, one end of which projects beyond the ends of the coil sections 65 2 and 3 for that purpose.

In forming the finished coil the coil section 2 is first wound upon the support 1. The end 5 may be secured by glue to the support 1 to facilitate the winding of the coil. 70 The coil section may be wound in any suitable manner and by any suitable means. I have ordinarily wound the coil in a cop winding machine in which the turns of the coil are automatically so laid on the support 75 that the ends of the coil are self supporting. After the coil section 2 is wound the inner end of the layer of paper or cloth forming the insulation 4 is ordinarily secured to the outer surfaces of the coil by glue or the like. 80 The outer end 8 of the conductor forming the section 2 is then soldered to the inner end of the conductor 9 which is preferably formed of tinned copper, and which is secured to the outer surface of the inner end of 85 the strip 4 in any suitable manner as by means of a piece of cloth or paper 12 which passes over the strip 9 and has its edges glued to the strip 4. After the end 8 is secured in place the strip 4 is wound about 90 the section 3. The strip 4 is formed near its outer end with a slit 13. The inner end 10 of the conductor forming the coil section 3 passes through the slit or kerf 13. After 95 the conductor forming the outer section is passed through the slit 13 and the strip 4 is wound about the coil section 2, the section 3 is wound, ordinarily by the same means employed to wind the coil section 2 and in the same manner. The slit 13 is so placed that 100 a portion of the conductor forming the outer winding section is separated from the body of the winding of the section 2 by one or more thicknesses of the strip 4. When the winding of the coil section 3 is completed a 105 few of the outer turns are ordinarily moistened with glue in order to set them and prevent their unwinding, after which the outer

end 11 of the conductor is secured to the projecting end of the strip 9 in any suitable manner as by a drop of solder. After the winding of the coil sections, or prior to their 5 winding, the end 5 and the terminal 7 are secured to each other and the connector 6.

In the form of my invention disclosed the connector 6 comprises a staple preferably formed of tinned copper the ends of which 10 are passed through openings formed to receive it in the support 1 and are then bent outwardly to lie against the inner surfaces of the support. The terminal 7, which is ordinarily of conductor stranded and considerably heavier than the wire composing 15 the windings of the sections 2 and 3, and may be provided at its outer end with a contact portion 14 adapted to be secured under a binding screw, etc., is fastened to the support 1 by the staple like conductor 6 beneath the yoke portion of which its terminal is passed. The inner bared end of the conductor 7 is bent outward as shown in Fig. 5. The end 5 of the section which is also bared 20 is then wrapped about the out-turned portion of the conductor 7 as at 5^a. After this is done the out-turned portion of the conductor 7 is bent down against the outer surface of the connector 6. A drop of solder 25 is then preferably employed to permanently secure the parts 5, 6 and 7 together. The parts 10, 6' and 7' are secured together in the same manner. With this construction it will be observed that in manipulating the 30 terminals in connecting up the coil or otherwise, no strain is put upon the turns of the winding sections tending to disarrange the windings or to break the conductors forming them. On the contrary any force exerted on 35 the terminal conductors 7 and 7' is imparted directly to the coil support 1 to which they are stapled. Where as in many cases, the conductors forming the coil sections 2 and 3 are very fine wires, anchoring of the terminals to the support is of great practical 40 importance. The connections of the terminal conductors to the coil supports and the ends of the coil windings are simple and easily formed, and possess excellent electrical as 45 well as mechanical advantages. These advantages are also possessed by the means employed for connecting together the terminals of the coil sections 2 and 3.

The particular coil shown in the drawings 50 is intended for use as a resistance in connection with measuring instruments or the like. If the turns of the coil sections 2 and 3 are wound in the same direction as described it 55 will be observed that the coil as a whole is non-inductive. If the coil is to be used for magnetizing purposes the coil sections are either wound in opposite directions or the coils are connected in a different manner. The use of the layer of insulating material 60 65 not only serves as a good mechanical sup-

port for the conductor 9, but by dividing the winding into sections it increases its electrical strength and diminishes its liability to break down.

What I claim as new, and desire to secure 70 by Letters Patent of the United States, is,—

1. In a coil for electrical purposes, a tubular support of insulating material, a pair of staples, one secured to each end of said support, a winding on said support formed 75 in two sections, one within the other, said sections being separated from each other by a strip of paper wound about the inner section, one end of the conductor forming one section being secured to one staple and 80 one end of the conductor forming the other section being secured to the other staple, and a strip of conducting material fastened to said strip with one end projecting by one end of the coil sections with the free end of 85 the conductor forming one section secured to the inner end of said conductor and the free end of the conductor forming the other section secured to the projecting end of said conductor. 90

2. In a coil for electrical purposes, a tubular support of insulating material, a pair of staples one secured to each end of said support, a winding on said support formed in two sections, one within the other, said sections being separated from each other by a strip of paper wound about the inner section one end of the conductor forming one section being secured to one staple and one 95 end of the conductor forming the other section being secured to the other staple, a strip of conducting material fastened to said strip of paper with one end projecting by one end of the coil sections with the free end of the conductor forming one section secured to the inner end of said conductor and the free end of the conductor forming the other section secured to the projecting end of said conductor, and terminal conductors anchored to said support by said staples. 100

3. As an article of manufacture, a core of insulating material, terminal conductors stapled to said core, and a conductor coiled about said core with its terminals secured to 105 said terminal conductors. 110

4. In combination, a coil support in the form of a tubular body of fibrous insulating material, a terminal conductor stapled to said support, and a conductor coiled about said support with one end connected to said 120 terminal conductor.

5. In a coil for electrical purposes, a support, a winding on said support in two sections arranged one within the other, a layer of insulating material between the sections, 125 a conductor mechanically supported by said insulating material, one terminal of each section of the winding being connected to said conductor. 125

6. In combination, a winding comprising 130

two concentric portions or sections, one within the other, insulation between the sections comprising layers of paper, a strip of conducting material mechanically supported between said layers, and terminals of each section secured to said conductor.

In witness whereof, I have hereunto set

my hand this twenty fourth day of October, 1905.

ELBERT W. JODREY.
